Des. 176,833
Patented Jan. 31, 1956

176,833

GEIGER GUN

Joseph Thomas Wallace, Phoenix, Ariz., assignor, by
mesne assignments, to Southern Instruments, Inc.,
Dallas, Tex., a corporation of Delaware

Application May 16, 1955, Serial No. 36,016

Term of patent 14 years

(Cl. D52—1)

FIG. 1.

FIG. 2.

FIG. 3

Figure 1 is a plan view of a Geiger gun showing my new design;

Figure 2 is a side elevational view of one side thereof; and

Figure 3 is a rear elevational view thereof.

I claim:

The ornamental design for a Geiger gun, as shown.
